DOUBLE PEDESTAL COCKTAIL TABLE

John B. Thorn, Lynchburg, and Andre Bus, Altavista, Va., assignors to The Lane Company, Inc., Altavista, Va., a corporation of Virginia

Filed Apr. 10, 1967, Ser. No. 6,606

Term of patent 14 years

(Cl. D33—14)

Fig. 1.

Fig. 2.

Fig. 3.

FIGURE 1 is a perspective view of the double pedestal cocktail table of our new design, a view from a substantially diagonally opposite perspective would be substantially the same in appearance;

We claim:

The ornamental design for a double pedestal cocktail table, as shown and described.
